Primary Examiner — Natasha Vujcic(74) *Attorney, Agent, or Firm* — Johnston IP Law, PLLC(57) **CLAIM**

The ornamental design for a grill for a cold storage system, as shown and described.

DESCRIPTION

FIG. 1 is a front perspective view of a grill for a cold storage system showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the Figures show portions of the grill for a cold storage system that form no part of the claimed design.
